UNITED STATES PATENT OFFICE.

WALTER M. CROSS, OF KANSAS CITY, MISSOURI.

METHOD OF MAKING PRODUCER GAS.

Application filed April 28, 1927. Serial No. 187,198.

This invention relates to improvements in gas producers and refers more particularly to a system in which gas of a relatively higher B. t. u. content is produced than that manufactured at the present time in gas producers utilizing either oil or coal as the charging medium.

This application is a continuation in part of a copending application, Serial No. 151,10 420, filed November 29, 1926.

Among the objects of the invention are to provide a gas producer which is not subject to coking or clinkering, free from shutdowns or low gas production periods, to provide a gas producer in which gas is made having a relatively high and uniform heat unit content, and to provide a gas producer relatively cheap to operate because of the economical use of the exhaust steam, and 20 waste heat from the gas made in the producer.

The system provides furthermore for the creation and maintenance of predetermined temperatures controlled at substantially the reaction temperature of the formation of carbon monoxide and hydrogen from coal and steam; to provide a coal dust gas producer which gives the contents great turbulence while the materials are undergoing 25 action, and in general to provide a system hereinafter described in more detail.

Fig. 1 is a diagrammatic side elevational view of the gas producing system.

Fig. 2 is a view taken along the line 2—2 35 in Fig. 1.

Referring to the drawings, at 1 is shown a coal hopper or bin, which communicates through a conduit 2 with a funnel like feed hopper 3, which is mounted upon the pulverizer 4. The pulverizer is driven by means of a motor diagrammatically shown at 5, or by any other suitable available source of power. The discharge from the pulverizer is delivered into the bin 6 and a screw conveyor 7 driven by a shaft 8 upon which a pulley 9 is mounted. The pulley 9 upon the shaft is driven from any suitable source of power, (not shown) operating at a uniform rate. The pulverized material, 45 which is fed by the screw conveyor passes into the annular duct 10, surrounding the gas producer near its top. To this annular space, or duct is also fed preheated air and superheated steam through the pipe or conduit 11.

The superheated steam is supplied by the

exhaust or discharge from the pump 12, or other source of steam supply introduced to line 14 through pipe 12^a. This pump 12 has a steam inlet line 13 and an exhaust or discharge line 14. The steam passing through the line 14 is directed through a heat exchanger 15 where it is brought in heat exchange relation with the highly heated gas withdrawn from the gas producer 16 through the pipe 17. After being preheated by the hot gas, the air and steam passes through pipe 18 and is circulated through a series of banks of coils designated as 19 and 20 in the air and steam superheater 21.

The air and steam superheater is fired either by gas, oil or coal, the combustion gases passing from the chamber 21^a over the baffle wall 22 and downwardly through the chamber in which the coil 19 is positioned. In the drawings an oil burner is diagrammatically shown at 21^b. These partially spent combustion gases are directed thence through a flue 23 and into the heat exchanger 24, where they are brought in heat exchange relation with cool air introduced through the pipe 25. After being cooled by the heat transfer in the exchanger 24 the combustion gases pass off to a flue 26.

The air, as suggested, introduced through the pipe 25 receives heat from the combustion gases in the exchanger 24 and passes through the line 26^a to an air pump 27 driven by a motor 28. A portion of the preheated air passing through the line 26^a may be diverted therefrom through pipe 26^b, and supplied to the burner 21^b utilized to heat the air and steam superheater. Thus, an accurate regulation of the preheated air is possible as a supply to the air and steam mixture in the gas making process and also an efficient utilization of the heat contained in gases in the flue 23 is effected. By means of the pump 27 the air is discharged through the second heat exchanger 15 in which it is combined with the steam introduced thereto through the line 14. In the exchanger 15 the preheated air and steam receives additional heat from the highly heated gas discharge from the producer through the line 17. The combined air and steam pass through the line 18 and receive their final raise in temperature in the superheater 21. The discharge line 29 controlled by a valve 30 serves as a means for diverting a portion of the steam exhaust from the pump while

the steam introduced to the system is regulated by a valve 31 in the line 14. This is in the case that excess steam is provided by the pump exhaust. As suggested, any discrepancy in the steam supply is made up through the line 12^a. In the same manner the injection of air is controlled by valves or dampers 32 in the lines 25 and 33 in the line 34 which connects the pump 27 with the 10 heat exchanger 15.

Auxiliary valves or dampers 26^b in the line 26^d and 26^e in the line 26^a furnish means for controlling the amount of preheated air combined with the steam and the portion 15 diverted to the burner.

Returning to the construction of the gas producer and the method of manufacturing gas from the fuel supplied through the screw conveyor and conduit 10 and the pre-heated air and superheated steam supplied through the line 11, these materials are introduced to the producer through tuyères or injection nozzles 35, which are set at an angle in order that the materials will be injected substantially tangentially into the circular producer. The producer is highly insulated to prevent in so far as is possible a loss of heat by radiation. The mixture or charge, as suggested, is given a whirling or 25 spiral motion on its injection into the producer and continues this whirling turbulence throughout its travel from the top of the producer to the bottom where the gas passes out through a baffle discharge line 17; the 30 hood 36 separating impurities and dust from the gas. The producer is equipped with a cleanout hole 37 which is covered by a removable plate 38. In the bottom of the producer is a liquid slag or residue draw-off 35 pipe 39, controlled by a valve 40.

The producer gas discharged through the line 17 passes through the heat exchanger 15 where it gives up a considerable part of its heat to the steam and air introduced 45 through the pipes 14 and 34 respectively. From the exchanger the gas passes through the pipe 41 into the dust separator 42, the marketable gas being delivered through a line 43 to a gas holder 44 from which it may 50 be drawn and disturbed by the pump 12, which has a suction line 45 communicating with the gas holder and a discharge line 46 for delivery of the gas to the mains or other desired delivery point.

In the system it is contemplated to heat 55 the air and steam to a temperature of reaction by passing it through the stack or flue of the superheater and gas cooler in series. By raising the mixture of air and steam to, or above, this reaction temperature, it is unnecessary otherwise to rely 60 upon a partial combustion of air in the producer to maintain the heat of reaction and thereby reduce the quality of the gas made.

The maintenance of the predetermined

temperature of reaction of the air and steam mixture may be effected by an automatic control diagrammatically shown at 48. This control is operated by a pyrometer 49, interposed in the line 11 operating a valve, 70 48^a, which regulates the fuel supply to the burner 21^b by which the air and steam superheater is fired.

The introduction of the air and steam mixture with the pulverized coal or oil particles is made to promote a high degree of turbulence in the reacting stage or producer, and while operating, effects not only an intimate combination of the constituents, but improves the character of the gas produced. 75 The process is continuous, as contrasted with the normal type of gas producer operation, in which a considerable period of the operation is taken up with the heating of the producer to the desired reaction temperature, or the temperature at which the air and steam will combine with the pulverized fuel or oil constituents to produce the quality of gas desired. 80

The producer is free from the difficulties 85 incidental to coking and channeling common to most gas producers. The coking and channeling materially slows down the production of the producer and seriously affects its efficiency. 90

In the present assembly or construction 95 there is provided a means for superheating steam and air mixtures to a predetermined temperature more or less according to the number of B. t. u.'s required in the gas. Thus, when a gas is desired having a high B. t. u. content, a very small amount of air and relatively large amount of steam, heated to a temperature say in the neighborhood of 2200° F., is used for introduction to the 100 producer to be combined with the coal dust. Temperatures will vary according to the character of the fuel used. Due to the fact that so much heat is brought in by means of the air and steam mixture, there will be 105 relatively little combustion required to keep the temperature of the gas producer at a proper reaction temperature for the economical production of the producer gas. 110

Under the above conditions the dilution 115 by nitrogen of the atmosphere is greatly minimized and accordingly the gas has a correspondingly higher heating value per cubic foot.

When transportation distances are relatively short, and it is not desired to produce a gas having such high B. t. u. value, the steam is superheated to a lesser degree. 120

In the present construction means are provided for pulverizing the coal and for blowing it or transferring it into the gas producer by means of superheated steam and air. The steam, preferably that taken from a pump, such as a gas distributing pump, 125 is superheated by being brought in heat ex- 130

- changing relation with the gas from the producer, and also by a supplementary heater. The gas from the producer may come off at temperatures of 2000° F., or more, and a 5 large amount of this heat may be conserved or utilized by transmission to the steam and air which is being supplied to the producer. A large amount of heat in the gas is ordinarily lost in the ordinary practices and the 10 recovery shown in the present custom will effect a saving so that the actual cost of heating the air and steam is greatly minimized over what has been the general practice heretofore.
- 15 Briefly, then, the novelty in the present invention lies primarily
- (1) In the making of producer gas from carbonaceous material, preferably in a finely divided condition. This carbonaceous material may consist of a coal, peat, coal dust, or heavy oil having a relatively high carbon content.
- (2) The system affords a process for producing a gas of relatively high B. t. u. content by superheating the steam and air required for the production of producer gas, to a predetermined temperature of reaction.
- (3) In the combination and utilization of the exhaust steam from pumps and the heat 20 exchanging equipment by means of which the heat of the gas discharged from the producer is transferred to the air and steam being introduced thereto: also the use of supplementary superheater for the air and 25 steam in combination with a heat exchanger in the flue of the superheater for taking advantage of the heat of the flue gases.
- (4) In a means for withdrawing the slag 30 while the gas producer is operating and for burning the fuel advantageously.
- (5) In a process in which the steam and air are heated substantially to or above the reacting temperature. A condition which promotes the rapidity of gas production during which reaction the carbonaceous material combines with the steam and air to form carbon monoxide and hydrogen in a desired and controlled amount.
- (6) In the placing of the inlet for the carbonaceous material and steam in a position on the producer so that the mixture is projected into the producer approximately tangentially to the inner surface of the cylindrical wall of the producer, thus giving greater turbulence to the constituents undergoing reaction, which promotes a more complete combination.
- I claim as my invention:
1. A method of making producer gas, comprising the steps of charging pulverized carbonaceous material to a stage of reaction, with mixed air and steam, said air and steam being heated to or above a predetermined temperature of reaction whereby producer gas results, and automatically controlling the 60 temperature of the air and steam mixture.
2. A method of making producer gas, comprising the steps of charging pulverized carbonaceous material to a stage of reaction, with mixed air and steam, said air and steam being heated to or above a predetermined temperature of reaction whereby producer gas results, and automatically regulating the 65 air and steam mixture to the predetermined temperature of reaction.
